UNITED STATES PATENT OFFICE.

CHARLES E. ROBERTS, OF OAK PARK, ILLINOIS.

DESIGN FOR A WHEEL-HUB.

SPECIFICATION forming part of Design No. 28,998, dated July 5, 1898.

Application filed February 3, 1898. Serial No. 669,017. Term of patent 14 years.

To all whom it may concern:

Be it known that I, CHARLES E. ROBERTS, a citizen of the United States, residing in Oak Park, in the county of Cook and State of Illinois, have invented a new and useful Design for a Wheel-Hub, of which the following is a specification.

Figure 1 is a perspective of a hub embodying my design. Fig. 2 is a side view of the same.

As shown in the drawings, the leading or material feature of my design consists in the

spherical form of the hub, each half or end A thereof being hemispherical.

Having described my invention, what I claim as new, and desire to secure by Letters Patent, is—

The design for a wheel-hub, substantially as herein shown and described.

CHARLES E. ROBERTS.
